US00D886101S

(12) **United States Design Patent** (10) **Patent No.:** **US D886,101 S**
(45) **Date of Patent:** **** Jun. 2, 2020**

(54) **SIGNAL CONVERTER OF GAME CONTROLLER**

(71) Applicant: **ZEROPLUS TECHNOLOGY CO., LTD.**, New Taipei (TW)

(72) Inventor: **Tsan-Hsing Pai**, New Taipei (TW)

(73) Assignee: **ZEROPLUS TECHNOLOGY CO., LTD.**, New Taipei (TW)

(**) Term: **15 Years**

(21) Appl. No.: **29/671,037**

(22) Filed: **Nov. 21, 2018**

(30) **Foreign Application Priority Data**

Sep. 20, 2018 (TW) 107305594

(51) **LOC (12) Cl.** **14-02**

(52) **U.S. Cl.**

USPC **D14/357**; D21/333

(58) **Field of Classification Search**

USPC D14/356, 357, 358, 433, 434, 239, 399, D14/400, 401, 454; D21/333; D10/104.1, 106.1, 106.6, 116.1, 61, 64, D10/75, 106.9

CPC G06F 13/38; G06F 13/382; G06F 13/385; G06F 13/387; G06F 3/00; G06F 3/0202; G06F 3/033; G06F 3/0334; G06F 3/0346; A63F 13/23; A63F 13/235; A63F 13/08; A63F 13/20; A63F 13/98; A63F 13/245

See application file for complete search history.

(57) **CLAIM**

The ornamental design for a signal converter of game controller, as shown and described.

DESCRIPTION

FIG. 1 is a perspective view of the signal converter of game controller showing my new design;

FIG. 2 is another perspective view of the signal converter of FIG. 1

FIG. 3 is yet another perspective view of the signal converter of FIG. 1;

FIG. 4 is a front view of the signal converter;

FIG. 5 is a rear view of the signal converter;

FIG. 6 is a left side view of the signal converter;

FIG. 7 is a right side view of the signal converter;

FIG. 8 is a top view of the signal converter; and,

FIG. 9 is a bottom view of the signal converter.

The broken lines depict portions of the signal converter of game controller that form no part of the claimed design.

1 Claim, 9 Drawing Sheets
